UNITED STATES PATENT OFFICE

165,683

COMBINED HOLDER FOR CONTAINER AND APPLICATOR

Albert B. Fournier and William D. Williams, Toledo, Ohio, assignors to National Laboratories, Inc., Toledo, Ohio, a corporation of Ohio

Application January 9, 1951, Serial No. 13,716

Term of patent 14 years

(Cl. D83—1)

To all whom it may concern:

Be it known that we, Albert B. Fournier and William D. Williams, citizens of the United States and residents of Toledo, Lucas County, Ohio, have invented a new, original, and ornamental Design for a Combined Holder for Container and Applicator, of which the following is a specification, reference being had to the accompanying drawing forming a part thereof.

In the drawing:

Figure 1 is a perspective view of a combined holder for container and applicator showing our new design;

Figure 2 is a top plan view of the holder; and Figure 3 is a bottom plan view of the holder.

We claim:

The ornamental design for a combined holder for container and applicator, as shown.

ALBERT B. FOURNIER.
WILLIAM D. WILLIAMS.
